CLAIM

The ornamental design for a transmitter case, as shown and described.

DESCRIPTION

FIG. 1 is a front plan view of the transmitter case of the instant invention;

FIG. 2 is a front elevational view of a second embodiment thereof, wherein the only difference resides in the single button feature;

FIG. 3 is a rear plan view of the transmitter case of the instant invention shown in FIGS. 1 and 2;

FIG. 4 is a side elevation view of the transmitter case of the instant invention shown in FIGS. 1 and 2. The opposite side elevation view is the mirror image;

FIG. 5 is a top end elevation view of the transmitter case of the instant invention; and,

FIG. 6 is a bottom end elevation view of the transmitter case of the instant invention shown in FIGS. 1 and 2.
